[57] ABSTRACT

There is disclosed a vehicle-mounted portable, hydraulically advanced earth boring drill, including a guide track, a movable carriage carried by and movable with respect to the guide track, a piston member mounted on the movable carriage and movable in response to pressure applied thereto, a support housing mounted on the movable carriage and having a drill carried thereon, the piston member being contained within a cylinder in fluid communication with a hydraulic fluid system, a removably engageable vehicle attachment mount carried by the guide track for accommodating the attachment of the apparatus to a vehicle and a counterbalancing support foot mounted on the guide track for counterbalancing the apparatus against the underlying support surface and the vehicle during use.

3 Claims, 4 Drawing Figures

FIG. 4

HYDRAULICALLY OPERATED PORTABLE BORING DRILL

BACKGROUND OF THE INVENTION

There are various occasions when it is desirable to drill bore holes into the earth. For example, various utility lines such as gas pipes, telephone lines, and the like, are buried in the earth and it is frequently necessary to locate such utility lines in order to avoid major damage to the same when other major construction is to be commenced at a given location. Alternatively, it is often desirable to drill into the ground to locate a gas pipeline to test the pipeline for a suspected gas leak. In still other applications, it is sometimes desirable to be permitted to drill a bore hole into the earth for the purpose of testing soil or for possibly anchoring elongated lugs into the ground.

In many of such instances, the necessary drilling must be done through hard surfaces, such as pavement, 20 blacktop, rock formations, and the like. In the past, it has usually been necessary to employ rather large and heavy duty drilling equipment necessitating heavy duty derrick equipment and several-men crews at the location involved. Such heavy duty equipment is usually 25 cumbersome and often times difficult to manipulate manually. For example, such equipment usually requires various types of supporting structures in order to hold and guide the drill during the drilling process. The end result is a structure which is not very compact and 30 cannot easily be transported from one location to the other. Furthermore, such drilling equipment usually requires several men to operate and therefore, increases the labor costs associated with drilling each bore.

Another drawback incident to such type of drilling equipment is the fact that usually, the only pressure available for driving the drill in its horizontal or vertical drilling movement is the speed of rotation of the drill bit and the weight of the drill. Hence, for example, U.S. Pat. No. 2,168,522 illustrates a drilling rig which is provided with a drill mounted on a support column by means of a carrier which is attached to the column with a chain drive. The chain drive merely serves the purpose of raising and lowering the drill, but otherwise the drill must rely upon the speed of rotation of the drill bit and the weight incident to the carrier and drill for its drilling pressure. It will further be noted that the drilling apparatus represented in the aforementioned patent is quite cumbersome and large and requires the use 40 of rails in order to move the drill into location.

Even the attempts to obviate these problems by introducing portability and compactness in such an earth boring rig has not met with complete success. For example, U.S. Pat. No. 3,464,655 illustrates another form of concrete boring drill which is shown to be carried by a support column mounted on a base support for securing the drill in both horizontal and vertical alignment during the drilling process. First, it will be noted that no feeding means is provided for the drill other than the speed of rotation of the drill bit and the weight of the drill, and hence, an effective feed mechanism for advancing the drill into the ground is not provided. Furthermore, while simplicity and portability is sought by the subject device, nevertheless, the device cannot be easily disassembled and transported from one location to another. In addition, it will be noted that the drill is positioned in virtually free standing relationship with

respect to the guide column and therefore, in the event the drill encounters any difficulty during the drilling process, either drill bits will be broken, or the drill could jump slightly whereby a perfectly cylindrical core 5 would not be obtained.

Other prior art devices have attempted to incorporate a feeding mechanism in order to pressure feed the drill during the drilling process to facilitate the coring operation. For example, U.S. Pat. No. 2,023,027 shows 10 a drill rig which is provided with a drill having a screw type feed mechanism to advance the drill during the drilling process. However, the fact that the feed mechanism is incorporated as a part of the drill, necessarily results in a drill which is rather large and cumbersome, and as evidenced in the U.S. Pat. No. 2,023,027, the device is not compact, nor is it easily transportable from one location to the other. It will be noted that the device requires a series of supports and mounts and furthermore, a platform must be constructed in order to support the entire drill rig at the desired location. Clearly, it would require more than one workman to set up such equipment and to operate the same.

Another attempt shown in the prior art for incorporating a feed mechanism into a drill shown in U.S. Pat. 25 No. 2,288,541. The structure shown in this patent incorporates a hydraulic feed mechanism which is built into the drill. The hydraulic feed mechanism operates to advance the drill during the drilling process, thereby to render the drilling process more efficient and hence 30 less costly. However, it will be noted that the drill rig as illustrated in this patent, comprises a rather complicated piece of machinery and hence, in the event of any breakage, obviously quite expensive repairs would be necessary. In addition, the drill mechanism itself is 35 quite large and therefore, quite heavy, and undoubtedly, would require more than a single man to operate. In addition, various types of support mechanisms must be provided in order to maintain the drill in position during the drilling process and hence, additional man 40 hours are necessary for the setting up and tearing down of such a drill rig.

Where attempts have been made at portability, portability in this art field generally involves derrick type trucks or other such other heavy duty equipment for 45 transporting the drill rig from one location to the other. For example, U.S. Pat. No. 2,766,114 shows a portable hydraulically operated drill rig which is portable only insofar as that it is mounted on a truck derrick. Clearly, 50 such a device is not compact, whereby it can be operated by a single individual. Furthermore, the complete structure requires various parts and mechanisms which, if damaged, require expensive repairs and a great deal of down time in terms of unused equipment. Various other types of drills and drill rig apparatus are shown 55 in the art, however, none of such drill rigs or apparatus has achieved a great degree of portability and compactness while at the same time incorporating an efficient feed mechanism for advancing the drill into hard surfaces, such as concrete, pavement, blacktop, rocky surfaces and sub surfaces and the like. In addition, it is desirable to provide a mechanism for assembly which minimizes expensive components and is easily and 60 readily repaired when damage occurs.

OBJECTS AND ADVANTAGES

It is therefore the principal object of this invention to provide a compact and portable earth boring drill as-

sembly which eliminates expensive component parts while at the same time providing a relatively light-weight and easily operable unit while at the same time providing an efficient earth boring drill.

Another object of this invention is a portable earth boring drill assembly which is removably mountable upon any vehicle and may be operated by a single workman.

Yet a further object of the invention is to provide a portable and compact earth boring drill assembly which may be removably mounted on a vehicle in stabilized relationship with respect to the surface to be drilled which also incorporates therein hydraulic feed means for advancing the drill during the boring process whereby the boring process is rendered more efficient and at the same time still only requiring the presence of a single workman.

A further object of this invention is to provide a vehicle supported portable boring apparatus for pressure drilling bores, including a guide track, a movable carriage, carried by and movable with respect to the guide track, pressure sensitive means associated with the movable carriage for moving the carriage in response to pressure applied against the pressure sensitive means, a support housing mounted on the movable carriage having drill means associated therewith, the support housing and drill means being movable with respect to the movement of the carriage, pressure means associated with the apparatus for providing pressure to the pressure sensitive means thereby to cause movement of the carriage, a power source associated with and in electrical communication with the apparatus for providing electrical energy to the apparatus, removably engageable vehicle attachment means mounted on the guide track for accommodating the attachment of the apparatus to a vehicle, and counterbalancing means mounted on the guide track for counterbalancing the apparatus as between the vehicle upon which it is mounted and the underlying surface to be drilled, such that the apparatus may be removably attached to a vehicle via the attachment means and firmly held in position by the counterbalancing means, while permitting a single workman to apply pressure to the pressure sensitive means to cause movement of the movable carriage which in turn causes a concomitant movement of the support housing and the drill means, the drill means then being permitted to drill an appropriate bore when electrical energy is supplied thereto from the power source.

In connection with the foregoing object, it is another object to provide a portable earth boring drill assembly of the type described, wherein the pressure sensitive means comprises a piston member mounted on the movable carriage for moving the carriage in response to the pressure means, and wherein the pressure means comprises a hydraulic fluid system which operates against the piston member to cause a concomitant movement of the movable carriage which in turn advances the drill carried on the movable carriage during the boring process.

A further object of this invention, in connection with the foregoing objects, is to provide a portable earth boring drill assembly of the type described, wherein the vehicle attachment means comprises an arcuate bumper mount whereby the drill apparatus may be mounted to a vehicle bumper, thereby to provide an easily transportable and easily mountable earth boring apparatus

such that the apparatus may be easily mounted and operated by a single workman.

In connection with the foregoing object, it is another object to provide an earth boring drilling apparatus of the type described wherein the counterbalancing means comprises a ratchet driven rod having a support foot mounted thereon at its free end and whereby the support foot may be ratchet driven into a tensioned counterbalancing posture against the underlying surface to be drilled and tensioned against the weight of the vehicle supporting the apparatus.

Further features of the invention pertain to the particular arrangement of the elements and parts whereby the above-outlined and additional operating features thereof are attained.

The invention, both as to its organization and method of operation, together with further objects and advantages thereof, will best be understood by reference to the following specification, taken in connection with the accompanying drawings in which:

FIG. 1 is a side elevational perspective view showing the earth boring drill assembly of the present invention as mounted on a vehicle and in its drilling posture;

FIG. 2 is a side elevational cross-sectional view showing the details of construction of the guide track, movable carriage, support housing, drill means and hydraulic system comprising the total assembly;

FIG. 3 is a top cross-sectional view showing the relationship between the guide track and movable carriage taken in the direction of the arrows along the line 3—3 of FIG. 2; and,

FIG. 4 is a side elevational view showing the power and hydraulic center associated with the drilling apparatus for providing the hydraulic fluid and electrical power to the apparatus.

Referring more particularly to FIGS. 1 and 2 of the drawings, the portable earth boring drill assembly is generally referred to by the numeral 10. The drill assembly 10 generally consists of a guided track 12 which is substantially U-shaped as shown in cross-section in FIG. 3, having a back wall 13, opposed side walls 14 and 15, extending outwardly from the back wall 13, the outer ends of the opposed side walls 14 and 15 terminating in inturned flanges 16 and 17 respectively, thereby forming an open track therebetween. As will be noted in FIG. 3, the interior surfaces of the side walls 14 and 15 are bevelled slightly outwardly from rear to forward with respect to the back wall 13, thereby to provide sufficient air space to permit ease of movement of the movable carriages will be described more fully hereinafter.

As will be noted from FIGS. 1 and 2 of the drawings, the guide track 12 is elongated in configuration and is sized so as to accommodate within the confines bounded by the back wall 13 and the side walls 14 and 15 thereof, a movable carriage 20. The movable carriage is similarly U-shaped in configuration having a back wall 21 and side walls 22 and 23 respectively. The movable carriage 20 is similarly elongated in configuration and is so sized as to be accommodated within the open track formed by the side walls 14 and 15 and in-turned flanges 16 and 17. It will further be noted that the side walls 22 and 23 of the movable carriage 20 terminate in front edges 24 and 25 respectively, which bump up against the interior surfaces of the inturned flanges 16 and 17. The movable carriage 20 is so sized as to be movable within the guide track 12, along the

vertical axis thereof. Hence, the overall dimensions of the movable carriage 20 measured from the front edges 24 and 25 of the side walls 22 and 23 to the rear of the back wall 21 is slightly less than the distances between the interior surfaces of the inturned flanges 16 and 17, and the interior surface of the back wall 13 of the guide track 12.

The movable carriage 20 includes a pair of support plates 28, which are mounted thereon, by means of a weldment 29, the support plate carrying a support housing generally referred to by the numeral 30. The support housing 30 is formed by a back wall 31, opposed side walls 32, a bottom wall 33 and a top wall 34. Each of the back walls 31, side walls 32, bottom wall 33 and top wall 34 are secured together by appropriate weldment as more particularly shown in FIG. 2 of the drawings. In addition the support housing 30 is provided with a drill carrier plate 35, which functions to support the drill in the manner described herein below.

It will be noted that the bottom wall 33 is provided with an enlarged aperture 36 which accommodates the forward end of the drill 80, therethrough, and hence, permits the drill bit 81 to extend outwardly and downwardly from the bottom wall 33 of the support housing 30. Most of the commercially available hand type drills, such as drill 81 are provided with a hand grip 82, adjacent the rear portion thereof, as well as the usual gun type hand grip 83 which carries the activating switch 84. The drill carrier plate 35 is designed to slide within the hand grip 82 of the drill 80, whereby the drill 80 is mounted and accommodated on the support housing 30, via the drill carrier plate 35 and the aperture 36 in the bottom plate 33. The top wall 34 is provided with an aperture 37 which accommodates therethrough a slip bolt 38, which secures the drill 80 in position when mounted in the support housing 30. It will be noted that the slip-bolt 38 slips in front of the hand grip 82 and hence, prevents the drill 80 from becoming disengaged from the support housing 30.

It will be apparent from the above description that since the support housing 30 is carried by the movable carriage 20, via the support plates 28, movement of the movable carriage 20 will cause the concomitant movement of the support housing 30 and the drill 30 which is carried thereby along the vertical axis of the guide track 12. Hence, as the movable carriage 20 is forced into a downward path of travel by the hydraulic system, which will be described hereinafter, the drill 80 is forced downwardly forcing the drill bit 81 downwardly into the ground.

The guide track 12 is provided with an attachment plate 40 adjacent the top portion thereof, the attachment plate 40 providing a point of attachment for carrying the cylinder 45. As shown in FIG. 2 of the drawings, the cylinder 45 is provided with a pair of attachment ears 46, thereby permitting the cylinder 45 to be bolted to the attachment plate 40, and firmly held in position. The lower end of the cylinder 45 is similarly attached to the guide track 12 so that the cylinder 45 is firmly held in position between the attachment plate 40 adjacent the top portion and a similar attachment arrangement adjacent its lower end.

The internal portion of the cylinder 45 is provided with a piston 47, the piston 47 having a piston head 49, at its top end, the piston head 49 having an O ring 50, thereby to provide a fluid tight seal of the piston 47

within the cylinder 45. As shown in FIG. 2 of the drawings, the movable carriage 20 is provided with a piston carrier rod 26 and it will be noted that the lower end of the piston 47 is mounted on the piston carrier rod 26 in fixed relationship. Any suitable mounting means may be utilized such as a bolt or a press-fit. The piston carrier rod 26 is mounted to the movable carriage 20 by means of a weldment, and hence, movement of the piston 47 in either an upward or downward path of travel will cause a concomitant movement of the movable carriage 20 and in turn, movement of the support housing 30 with the drill 80 mounted thereon.

The cylinder 45 is, of course, a closed cylinder and is therefore fluid tight. Hence, by providing hydraulic fluid either above or below the piston head 49 of the piston 47, the piston 47 will be caused to move either upwardly or downwardly respectively.

The details of construction relating to the hydraulic system are shown in FIGS. 1 and 2 of the drawings. Adjacent the top portion of the guide track 12 is mounted a U-shaped valve support 55. A control valve 57 is carried on the valve support 55 and permanently mounted thereon by means of a weldment or other suitable mounting means. The control valve 57 is provided with a handle 59, which permits the operator to select the flow path desired, depending upon whether the piston 47 is to be moved upwardly or downwardly. A hydraulic supply line 60, extends from a hydraulic fluid source such as is shown in FIG. 4 of the drawings, and the opposed end thereof is connected to a control valve 57, by means of a fluid line connector 62. A hydraulic exhaust line 64 is also provided and extends from the hydraulic fluid source and is connected to the control valve 57 via a fluid connector 66. Hence, hydraulic fluid may be supplied to the interior portion of the cylinder 45 through the supply line 60 and may be exhausted there from via the exhaust line 64.

An upper feed line 67 is provided which is connected to the control valve 57 via a fluid connector 68 at its one end and is connected at its other end to the upper portion of the cylinder 45 via another fluid connector 69. The upper feed line 67 is provided to permit hydraulic fluid to be fed into the upper portion of the cylinder 45 above the piston head 49 of the piston 47. Similarly, a lower feed line 70 is connected at its one end to the control valve 57 via fluid connector 71, and at its other end is connected to the lower end of the cylinder 45 via another fluid connector 72. Of course, the interior portion of the control valve 57 is well known in the art and manipulating the handle 59, the desired fluid flow path may be selected so that fluid will flow either through the supply line 60, exhaust line 64, upper feed line 67, or lower feed line 70. For example, where it is desired to supply a fluid under pressure to the upper portion of the cylinder 45 above the piston head 49 of the piston 47, the appropriate fluid flow path is selected by moving the handle 59 of the control valve 57 to the proper position, which will then cause the fluid to flow through the supply line 60, into the control valve 57, and into the upper feed line 67. As the fluid under pressure is supplied to the cylinder 45 above the piston head 49 of the piston 47, the piston 47 will be forced downwardly. Since the lower end of the piston 47 is permanently secured to the piston carrier rod 26, and hence, the movable carriage 20, the movable carriage 20 will move downwardly and carry with it the support housing 30, with the drill 80 mounted

thereon. Alternatively, should one desire to move the piston 37 in a vertically upward direction, the appropriate fluid flow path is selected by manipulating the handle 59 of the control valve 57, such that fluid is supplied via the supply line 60 through the control valve 57 and into the lower feed line 70. Fluid will then be supplied to the under-portion of the piston head 49 and force the piston 47 in an upward direction. During the upward travel of the piston 47, obviously any fluid existing above the piston head 49 will be forced out of the cylinder 45 through the upper feed line 67 and through the control valve 57 and out of the system via the exhaust line 64.

It will now become apparent that once the drill 80 has been mounted on the support housing 30, and the drill 80 plugged into a power source 100, the operator of the drilling unit may open the hydraulic lines by manipulating the handle 59 of the control valve 57 with one hand while the drill switch 84 is manipulated with the operator's other hand, thereby starting the drilling process and the hydraulic system operating to force the drill in a downward path of travel such that the drill bit 81 is forced into a boring posture with respect to the ground. It is contemplated that snap-on type drill bits 81 are utilized in connection with the subject invention such that series of drill bits may be snapped together in order to bore deeper holes into the ground.

In the preferred embodiment, the piston 47 has a stroke of approximately 30 inches, so that with each downward movement of the drill, an overall path of travel of 30 inches will be travelled by the drill before the operator need snap on another drill bit 81, raise the support housing to its upper posture, and continue drilling downwardly. This process may be repeated as many times as is necessary in order to drill to the desired depth.

In FIG. 1 of the drawings, the vehicle attachment means is more clearly illustrated. It will be observed that the rear surface of the back wall 13 of the guide track 12 is provided with a rod carrier plate 75 which is mounted thereon by means of weldments 76. The rod carrier plate 75 carries the tensioning rod tube 85 as is more particularly shown in FIG. 2 of the drawings. The tensioning rod tube 85 accommodates a ratchet driven tensioning rod 87 thereon, the lower end of the tensioning rod 87 terminating in a support foot 89 which is designed to fit flushly against the underlying support surface, such as the ground. The upper end of the tensioning rod tube 85 is provided with a tensioning ratchet 90 which is operated by means of a handle 91 such that a repeated rotation of the handle 91 in a ratchet movement will cause the tensioning rod 87 to be moved downwardly until the support foot 89 comes into tensioned contact with the ground.

The back surface of the tensioning rod tube 85 has a vehicle mount carrier plate 92, mounted thereon by means of a weldment or other suitable mounting means, the vehicle mount carrier plate 92 having an arcuate vehicle bumper mount 94 mounted thereon by means of appropriate weldments, or other similar permanent mounting means. The arcuate bumper mount 94 is designed in the same style as the common ordinary car bumper jack and hence, is designed to mount to a vehicle bumper as shown in FIG. 1 of the drawings.

In order for the operator to mount the drill assembly 10 to a vehicle, the arcuate vehicle bumper mount 94

is positioned about a vehicle bumper after which the operator rotates the handle 91 of the tensioning ratchet 90 with a ratchet movement in order to drive the tensioning rod 87 downwardly until the support foot 89 is firmly tensioned against the ground. It will therefore be appreciated that the drill assembly 10 is counterbalanced as between the weight of the vehicle which tends to force the drill assembly in a downward direction while the tensioning rod 87 and support foot 89 tend to push the drill assembly 10 in an upward direction. Hence this counterbalancing affect results in great stability of the drill assembly 10 when mounted on a vehicle prior to commencing the drilling operation.

Once the drill assembly 10 has been mounted on the vehicle as indicated above, the operator may then commence the operation of the drill assembly 10 by mounting the drill 80 in position on the support housing 30 and attaching the first length of drill bit 81. Once the drill 80 has been mounted and properly connected to the power source 100, the operator may then open the hydraulic control valve 57 by manipulating the handle 59 to obtain the desired flow path of fluid within the appropriate feed lines. Hence, to move the support housing with the drill 80 mounted thereon downwardly, the handle 59 is moved to the position to permit fluid under pressure to enter into the control valve 57 through the supply line 60, and from there through the feed line 67 into the cylinder 45 above the piston head 49. The pressure of the fluid will therefore move the piston 47 in a downward direction which causes the concomitant movement of the movable carriage in a downward direction, and hence, the support housing 30 and drill 80 which is mounted thereon. In this manner, it is clear that it is not necessary for the operator to apply any pressure to the drill assembly 10 during the drilling operation. Once the complete stroke of the piston 47 has been reached, the operator may turn off the electrical power, snap on another drill bit 81, recycle the support housing in an upward direction by supply fluid under pressure to the undersurface of the piston head 49, causing the piston 47 to rise and therefore, commence another downward cycle of the piston 47.

The power source 100 and the supply source for the hydraulic fluid or other fluid under pressure is preferably carried in a control box 105, which may be mounted on the vehicle which is utilized in connection with carrying out the drilling operation. Due to the size and compactness of the drilling assembly 10, provided by virtue of this invention, it is apparent that when the unit is disassembled and stored in the vehicle, a minimum of storage space is consumed and in fact, the set up and take down of the drill assembly 10 may be accomplished by a single operator. As has been pointed out above, not only may the unit be set up and taken down by a single operator but the unit may be completely operated by a single operator.

As mentioned above, the interior surfaces of the side walls 14 and 15 are bevelled outwardly from rear to forward with respect to the back wall 13. In this manner, air spaces are provided as between the side walls 22 and 23 of the movable carriage 20, and the side walls 14 and 15 of the guide track 12. This construction minimizes frictional contact as between the opposed side walls and thereby permits ease of movement as between the movable carriage 20 and guide track 12. In addition, the air spaces permit an air cooling affect as

the movable carriage 20 is pressure driven during the drilling operation.

It will therefore be appreciated that by virtue of the present invention a very compact and easily transportable earth boring drill assembly has been provided which, at the same time, is provided with pressure feed means associated therewith for driving the drill during the drilling process. In addition, the assembly of the present invention utilized fairly inexpensive component parts and is designed to accommodate the standard type portable industrial drills which are presently available. In this connection, it will be appreciated that in the event the drill should break down, the operator may easily replace the drill by merely removing the slip bolt 38, and removing the drill 80 to effect replacement thereof. Similarly, if leaks should develop in the hydraulic system, such as leaks in the fluid connector they may be easily repaired by simply replacing the fluid connectors at any point where same are leaking. In most instances, such repairs and replacements may be effected at the scene of the drilling operation, such that there is a minimum of down time when repairs are necessitated. In addition, the drilling assembly of the present invention permits a reduction in terms of the cost of labor, since equipment may be set-up and completely operated and then taken down by a single operator. Another advantage achieved by virtue of the drill assembly of the present invention is the fact that the operator may change drills at the drilling location, where it is determined that a higher horsepower drill is necessary. For example, should the operator be confronted with drilling through a substrate which is of much greater strength than originally anticipated, the operator may easily remove one drill and replace same with a higher horsepower to accomplish the desired drilling.

It is therefore appreciated that all of the above objects and advantages have been accomplished by means of the drill assembly described herein.

While there has been described what at present is considered to be the preferred embodiments of the invention, it will be understood that various modifications may be made therein and it is intended to cover in the appended claims all such modifications as fall within the true spirit and scope of the invention.

What is claimed is:

1. A vehicle supported portable boring apparatus for pressure drilling bores comprising, in combination, a guide track, a movable carriage carried by and movable with respect to said guide track, a cylinder mounted on said guide track,

10
5
15
20
25
30
35
40
45
50

10
a piston member carried within said cylinder having an upper free end and a lower end mounted on said movable carriage, said piston member being in fluid tight sealing relation with respect to said cylinder, a pressurized fluid system connected to said cylinder at its upper and lower ends whereby fluid under pressure may be introduced into said cylinder alternatively at its upper and lower ends, thereby to cause alternate upward and downward movement of said piston member within said cylinder, flow control valve means associated with said pressurized fluid system for controlling the direction of fluid flow within said pressurized fluid system, a power source associated with and in electrical communication with said apparatus for providing electrical energy to said apparatus, a bumper mount carried by said guide track to permit the removable engagement of said apparatus to a vehicle bumper, and a movable support foot mounted on said guide track for counterbalancing said apparatus as between the vehicle upon which said apparatus is mounted and an underlying support surface, whereby said apparatus may be removably attached to a vehicle via said bumper mount and firmly held in position by said support foot, and pressure applied to said piston member from said pressurized fluid system thereby to cause movement of said piston within said cylinder, and cause a concomitant movement of said movable carriage which, in turn, will cause a movement of said support housing and said drill means to effect the drilling operation.

2. The boring apparatus as set forth in claim 1 above, wherein said movable carriage comprises a movable channel positioned within and movable with respect to said guide track, a pair of support plates mounted on said movable channel and extending outwardly from said guide track,

a drill carriage housing fixedly mounted on said support plates, a drill removably mounted on said drill carriage housing, said drill provided with at least one rotary boring bit, whereby said drill may be removably mounted on said drill carriage.

3. The boring apparatus as set forth in claim 2 above, which further includes lock means associated with said drill carriage for locking said drill in position when mounted on said drill carriage.
